UNITED STATES PATENT OFFICE.

EDWARD SMALLWOOD, OF ELYRIA, OHIO.

STONE-PLANING MACHINE.

SPECIFICATION forming part of Letters Patent No. 447,372, dated March 3, 1891.

Application filed March 18, 1890. Serial No. 344,368. (No model.)

To all whom it may concern:

Be it known that I, EDWARD SMALLWOOD, of Elyria, in the county of Lorain and State of Ohio, have invented certain new and useful 5 Improvements in Stone-Planing Machines; and I do hereby declare the following to be such a full, clear, and exact description of the invention as will enable others skilled in the art to which it appertains to make and use the 10 same.

My invention relates to stone-planing machines having a reciprocating table and a revolving cylinder carrying the tools for planing the stone; and the objects are to provide 15 a machine of the above-described class with means for revolving the cylinder in both directions and for simultaneously reversing the motion of both the cylinder and table, whereby this class of machines is adapted to plane 20 the stone resting on the table during both the backward and forward movements thereof, to provide novel means for adjustably securing the stone-cutting tools in the cylinder, and to provide mechanism whereby the tools 25 may be ground and kept in condition to plane the stone without stopping the planing operation.

To this end it consists in the construction and combination of parts herein described, 30 and shown in the drawings, all of which will be definitely pointed out in the claims.

In the drawings, Figure 1 is a top plan view of my improved machine. Fig. 2 is a side elevation of the machine, looking at the same 35 in the direction indicated by the arrow 2, shown in Fig. 1. Fig. 3 is a side elevation of the same from the direction indicated by the arrow 3. Fig. 4 is an end view looking in the direction indicated by the arrow 4. Fig. 6 is 40 a transverse sectional view through the cylinder to which the planing-tools are secured. Fig. 5 is a transverse sectional view through the cylinder, showing modified means for securing the planing-tools in the cylinder. Fig. 7 is a front elevation of the grinding-wheel and 45 the mechanism whereby the same is moved transversely of the machine while said wheel is revolving. Fig. 8 is a view of one of the planing-tools.

50 I will now proceed to describe in detail the machine shown in the drawings, and for the purpose of adding clearness to the explana-

tion I will refer to the various parts shown in the several figures by reference-letters.

A represents the base or bed of the machine. Attached to said base and on the opposite side thereof are the two upright side frames B, which are connected at their tops by a suitable cross-beam B'. These parts—to wit, the base and side frames and the connecting cross-beam—constitute what may be termed the "frame" of the machine, and all of the movable parts hereinafter described are mounted upon and supported by this frame-work in substantially the manner 65 specified. Extending lengthwise of the bed and secured thereto at a suitable distance apart are the ways A' A', on which the work-table C slides back and forth. The ways A' A' in the base and the ribs on the under side 70 of the table, which slide therein, may be of any suitable shape or construction, provided they are adapted the one to the other. The construction of these parts shown in the drawings is as follows: The ways are rectangular 75 and a suitable number of friction-rollers a are placed in each. The ribs on the table are also rectangular, and the bottom parts thereof rest and slide upon these friction-rollers.

G represents the main driving-shaft of the 80 machine, which is mounted in suitable bearings in the base and extends transversely across the machine below the work-table C. Upon one end of this shaft are mounted two loose pulleys, between which is a double 85 clutch L L, of any approved construction, adapted to engage with either pulley or to be disengaged from both. One of these pulleys is driven in one direction, and the other pulley in the contrary direction. Therefore, according as the clutch engages with the one or the other of these pulleys will the direction in which the machine is run be determined. On the opposite end of the main shaft of the machine is a pinion g', which engages one of 95 a train of gears, the last of which (indicated by the letter i) is secured to a shaft I, suitably mounted in the frame-work and extending to near the transverse middle of the machine beneath the table C. The purpose of 100 this train of gears is, first, to transmit power from the main shaft to the shaft I, and, second, to differentiate the speed of said two shafts. The relative sizes of said gears and

pinions may be such that the speeds of said two shafts may bear any desired relation to each other. Secured to the under side of the table C is a rack c, and mounted upon the shaft I is a pinion i', which engages with said rack, whereby the table is caused to reciprocate—that is to say, to move in either direction, depending upon the direction in which the shaft I revolves.

10 J J represent two vertically-disposed revolute screws suitably mounted adjacent to the side frames B. Each of these screws passes through a suitably-threaded orifice in a movable block K. On the top of each screw is a worm-wheel j, which engages with a worm H, mounted in suitable bearings on the cross-beam B'. On one end of this worm are secured tight and loose pulleys suitably belted to a counter-shaft, whereby the worm may be revolved in either direction and the blocks K 15 be moved as desired. In addition to their engagement with the screws J the blocks K are also guided by their engagement with suitable vertical grooves in the side frames B. These blocks K are provided with journal-boxes, in which the ends of the shaft d are mounted, and a cylinder D is secured rigidly to said shaft. The planing-tools are suitably secured to this cylinder in a manner hereinafter described. The cylinder, it will be seen, is moved to a greater or less distance above the surface of the reciprocating table as the boxes in which its shaft is mounted are moved by the mechanism previously described. The cylinder itself is revolved by the following mechanism, to wit: A vertical shaft N is suitably mounted in brackets secured to the side frame to which it is adjacent. A beveled gear d' is secured to the end 35 of the shaft d, and it meshes with the beveled gear N', which is mounted in a bracket k, secured to the block K on that side of the machine. A tongue-and-groove connection between the vertical shaft N and the beveled gear N' causes both to revolve together whatever be the elevation of the beveled gear. This vertical shaft N is driven by the main shaft G by means of a train of gears, which also afford means whereby the relative speeds 40 of the main shaft and vertical shaft N may be differentiated.

The stone-cutting tools Q are secured to the revolving cylinder and project from its periphery in a spiral line. As shown in the drawings, the tools are secured in radial sockets in said cylinders, whereby the tools cut the stone when the cylinder is revolving in either direction. The tools are set in the cylinder so that the cutting-edges of succeeding tools 45 overlap each other slightly, as shown, which prevents the formation of a ridge on the planed face of the stone between the points of contact therewith of adjacent tools. In the preferred construction this overlapping of the outer edges is produced by flaring or spreading the tools sidewise at and near the cutting end thereof.

Two methods for securing the tools in the cylinder are shown in the drawings, both of which have certain common features. The cylinder is provided with radial sockets suitably disposed, as shown in Fig. 5. Each socket contains a radially-movable bar R, having a knee r at substantially right angles to its body. The tool enters the socket, and its end abuts against said knee. The knee-bar is moved out or in by a screw S, whereby the projection of the tool is adjusted. When the tool is in the proper position, it is secured in placed by a wedge or wedges s or other suitable means. The modified mechanism includes a removable box T, adapted to be secured in the socket in the cylinder, always entering the same distance. This distance may be determined by a flange on the box 85 or by the depth of the socket. The box contains the same adjustable knee-bar and is provided with the set-screw for adjusting it, all of which are shown in Fig. 5. When properly adjusted, the tool is secured by a 90 wedge or wedges, as in the former case. The boxes themselves are secured in the cylinder by wedges or other suitable mechanism.

The operation of the machine as thus far explained is as follows: The stone to be planed is placed upon the reciprocating table. The revolving cylinder is properly adjusted by moving blocks K, in which said cylinder is journaled, up or down, as the circumstances require. One of the clutches L is thrown into engagement with its pulley and the machine starts, the table moving, for example, to the right, as shown in Fig. 3, in which case the cylinder, which simultaneously begins its revolution, revolves in the direction indicated by the arrow in said figure. When the table has traveled as far as desired in that direction, a lug c', attached to said table, engages with the shifting-lever U, and thereby shifting the clutch on the main shaft and connecting the same with the pulley which has hitherto been running freely, whereupon both the table and the cylinder reverse the direction of their motion. The cylinder is moved downward by the means hereinbefore described, 115 and the tools by reason of their radial projection from the cylinder will cut the stone upon the table during this reverse motion of the parts, as above described.

It may sometimes be desirable to run the table while the cylinder is stationary or to run the cylinder while the table is stationary, and in order that this may be done two clutches W and V are provided. The clutch W when closed connects the pinion g with the main shaft, whereby the cylinder is revolved, as heretofore explained. The clutch V when closed similarly connects the pinion g' with the main shaft, whereby the table C is connected with and driven by said shaft. When either of these clutches is opened, the mechanism with which it is connected—that is, either the cylinder or the table, as the case may be—becomes stationary.

It is clear that the character of the work performed by the cutting-tools is such that they will require more or less frequent grinding to preserve their cutting-edges. Under ordinary circumstances it would be necessary to remove these tools from the cylinder and grind them and then replace and adjust them, during which time the machine would be idle. To avoid this serious loss of time I provide a grinding-wheel X, mounted in vertically-movable boxes x x, and in such relation to the revolving cylinder that it is adapted to grind the tools as said cylinder revolves and without their removal from the sockets in which they are secured. By this combination of parts no time is lost, and the tools when once adjusted need no further adjustment until they are so far ground away as to be no longer available for cutting stone. The boxes x x, in which this emery or grinding wheel is mounted, are provided with screw-threaded orifices, through which pass vertically-disposed screws Y, having a worm-wheel y on the top. A worm Z, mounted in suitable bearings and extending across the machine, engages with these worm-wheels and is revolved by a sheave or other suitable means when it is desired to move the boxes up or down. In order to prevent the tools from forming grooves in the grinding-wheel, said wheel is automatically given an axial movement by means of a slowly-revolving disk E, which is set on its shaft obliquely. The edge of this disk engages between two collars x' x' on the shaft of the grinding-wheel, and thus, while it in nowise interferes with the rapid revolution of said shaft, slowly moves it back and forth a short distance transversely of the machine.

Having thus described my invention, what I claim as new, and desire to secure by Letters Patent, is—

1. In a stone-planing machine, in combination, a reciprocating table, a vertically-adjustable revolving cylinder having stone-cutting tools projecting radially from its surface, and mechanism for simultaneously reversing the motion of both the table and cylinder, substantially as and for the purpose specified.

2. In a stone-planing machine, in combination, a reciprocating table, a vertically-adjustable revolving cylinder having stone-cutting tools projecting radially from its surface, a main shaft, and suitable connections between said shaft and the table and cylinder,

respectively, two reversely-revolving pulleys 55 mounted loosely on said shaft, a double clutching device secured to said shaft, and mechanism operated by the table for throwing said clutching device out of engagement with one of said pulleys and into engagement with the other, whereby the direction in which the shaft revolves is reversed, with the result of simultaneously reversing the motion of both the table and cylinder, substantially as and for the purpose specified. 65

3. In a stone-planing machine, in combination, a reciprocating table, a revolving cylinder having stone-cutting tools projecting radially from its surface, mechanism for simultaneously reversing the motion of table and cylinder, a revolving grinding-wheel parallel to said cylinder, and mechanism for moving said grinding-wheel toward and from said cylinder, substantially as and for the purpose specified. 75

4. In a stone-planing machine, in combination, a reciprocating table, a vertically-adjustable revolving cylinder having radial sockets for the reception of the stone-cutting tools, and the following mechanism for holding and adjusting said tools within the socket, to wit: a radially-movable knee-bar, a screw the inner end of which engages with a threaded socket in said knee-bar, the outer end of said screw being accessible from outside the cylinder, and a wedge for holding the tool firmly in place with its end resting against the knee of said bar, substantially as and for the purpose specified. 85

5. In a stone-planing machine, in combination, a reciprocating table, a vertically-adjustable revolving cylinder having radial sockets, and the following mechanism for adjusting the position of the tools and for securing them in said radial sockets, to wit: a removable box T, having a flange around its upper edge, a knee-bar inclosed within said box, a screw S, passing through the upper part of said box and engaging with said knee-bar, a wedge for securing the tool within said box with its end resting against the knee of said bar, and a wedge for securing the box within the socket, substantially as and for the purpose specified. 95 100

EDWARD SMALLWOOD.
